UNITED STATES PATENT OFFICE

2,498,367

ELECTRICAL MUSICAL INSTRUMENT

Laurens Hammond, Chicago, and John M. Hanert, Park Ridge, Ill., assignors to Hammond Instrument Company, Chicago, Ill., a corporation of Delaware

Application September 15, 1944, Serial No. 554,180

8 Claims. (Cl. 84—1.21)

1

Our invention relates generally to electrical musical instruments and more particularly to a greatly improved form of chorus tone generating system for instruments of this character.

It is the fundamental object of our invention to provide an improved electrical musical instrument in which there may be introduced a chorus effect which is of much greater extent and tonal beauty than has previously been considered possible.

A further object is to provide an electrical musical instrument having chorus generating equipment in which the various electrical tone generators are effective to supply groups of relatively pure tones having average frequencies corresponding to the notes of the musical scale and in which the percentage of pitch deviation between the generators of each group differs from that of the others in a manner to produce an improved chorus effect.

Another object of our invention is to provide chorus generating equipment in which a plurality of generators are employed for each of the notes of the musical scale and in which the corresponding chorus generators supplying the various octaves of the musical scale frequencies do not bear exact integer relations but are generated in a manner to deviate progressively from the standard octave integer frequency relationship to a diminishing extent with increasing frequency.

A further object of our invention is to provide an improved electrical musical instrument incorporating chorus generators in addition to solo generators, in which the various musical tone colors are electrically synthesized, and in which the chorus generators supplying the fundamental of a tone differ from each other in pitch to a greater extent than the chorus generators supplying the higher harmonics.

It is another object of our invention to provide chorus generating equipment in which the extent of the chorus effect of each tone produced by a group of simultaneously sounded generators is achieved at a theoretical maximum, independently of the particular tone quality employed.

It is another object of our invention to provide chorus generating equipment in which the tuning of the chorus generators is not held to a constant percentage with respect to the nominal frequencies of the notes of the musical scale, but instead varies, depending upon the absolute values of the nominal frequencies.

Other objects will appear from the following description, references being had to the accompanying drawings in which:

Figure 1 is a fragmentary plan view of a portion of the chorus generator;

Figure 2 is an enlarged sectional view of two

2

pairs of chorus tone wheel generators taken on the line 2—2 of Fig. 1;

Figure 3 is a schematic circuit diagram showing a portion of the solo as well as the chorus generating system and illustrating the electrical circuits associated therewith;

Figures 4, 4a and 4b together constitute a chart setting forth, in tabulated form, various physical constants of the generating system;

Figure 5 is a curve illustrating the maximum permissible percentage deviation of two chorus generators for different quality tones at different pitches;

Figure 6 is a curve comparing the chorus frequencies generated with the maximum permissible percentage deviation from the true pitch; and

Figure 7 is a chart setting forth, in tabulated form, various physical constants of a modified form of generating system.

In order to appreciate fully the effect produced by the apparatus of our invention it is necessary to have a clear understanding of the frequency characteristics of chorus tone phenomena and particularly of the basically new acoustic principle upon which the chorus apparatus of our invention operates.

It has long been recognized that the richness of most musical tones may be greatly enhanced by the utilization of several tone generating sources, all of which sound simultaneously to produce a chorus effect. This effect is commonly observed in orchestras where it is not unusual to see a relatively large number of musicians playing the same note on the same kind of instrument. The explanation of the resulting beauty of their composite tonality resides in the fact that the musicians inadvertently play at slightly different pitches. The result is an interesting and pleasing tonal undulation. If all the musicians were to play at exactly the same pitch, the resulting effect would be substantially identical to that produced by a single player save for a somewhat increased loudness due to the multiplication of the number of instruments.

These inadvertent differences in pitch, while productive of a very noticeable change in quality are actually very small, their mutual deviation factor being a fraction of a percent. Apparatus for producing similar chorus effects have also been provided in organs, accordions, harpsichords and the like. When the chorus effect is desired, instruments of this class make use of several independent tone generators of slightly differing pitch rendered simultaneously effective upon the depression of a single playing key. That these chorus effects are beautiful cannot be denied. Their effect musically is of fundamental importance in orchestras, keyboard instruments, and choruses of voices.

60

Builders of musical instruments have found that chorus effects are desirable only to the extent that the pitch difference between the several simultaneously sounded tone generators is relatively limited, in the order of .4%. If this percentage be increased, the effect tends to become musically unacceptable because the ear then resolves the overall chorus effect into its individual tonal sources and perceives them as separate dissonant tones, and consequently evaluates the overall effect as an imperfection in tuning.

We have discovered that tone quality is of vital importance in determining the extent to which the pitches of the individual tone generators comprising the chorus may deviate. In general, the brighter tones of the strings and reeds may not deviate in pitch as much as the more mellow tones such as the organ diapason and flute qualities. We have found that the maximum percentage deviation in pitch is permissible for pure sinusoidal tones. The following table illustrates the maximum extent of pitch deviation allowable when two independent sources of identical intensity and tone quality and the average pitch of which is 512 C. P. S., are sounded simultaneously:

Tone Type	Maximum Allowable Percentage of Pitch Deviation
	Percent
Orchestral string tone	0.34
Orchestral reed (trumpet)	0.46
Organ diapason	0.6
Orchestral flute tone	0.9
Pure sinusoidal tone	1.4

The above figures strikingly show the interdependence of tone quality and extent of allowable pitch deviation between the chorus tone generators. These figures are based upon observations made by a trained musician. Similar observations by another musician might provide slightly different results, but tests indicate that there is substantial agreement among musicians as to the permissible deviation for this chorus effect.

We have further discovered that the average pitch of the tone plays a major role in determining the maximum allowable percentage of pitch deviation. The curves of Fig. 5 clearly shows this effect for the above qualities. Some of the interesting deductions which may be drawn from these curves follow:

(1) The maximum permissible percentage pitch deviation for very complex notes such as the orchestral strings and reeds is definitely limited in extent and rises but very little for the lower frequencies. This may be understood by considering that the pitch of the string tone is extremely well defined because of its long harmonic series, all the frequencies of the tone being effective in a subjective manner to enable the ear accurately to ascribe a definite pitch to the sound. Thus a relatively small deviation in pitch of these bright tone generators results in the average listener being able to perceive the individual generators as separate dissonant tones.

(2) Of the five curves shown, the curve for the sinusoidal tone is especially interesting in that it shows by far the greatest permissible percentage pitch deviation between the chorus tone generators. This remarkable phenomenon is probably due to the fact that the sinusoidal tone is unique among all tone qualities in that it excites

but a single sensory element in the listener's inner ear and thus its tonal pitch is perceived without the benefit of any subjective pitch reinforcement effects. Thus the sinusoidal tone represents, in a theoretical as well as a practical sense, the most difficult tone to which the ear may accurately assign a definite pitch. Consequently, the perceptive powers of the ear allow a very wide deviation in pitch between the two sinusoidal chorus generators before being able to resolve their separate pitches.

(3) The area under each of the curves is indicative, in a general way, of the extent of permissible chorus effect. It is at once apparent that the chorus effect may be greatest for the pure sinusoidal tone quality and should be least for the brilliant string tone quality. It is further seen that the ratio of these two extreme qualities is very large. However, the extensive chorus possibilities of the sinusoidal tone quality have been of little practical value because the sinusoidal quality of tone of itself is exceedingly uninteresting, being totally devoid of harmonic overtones.

From the preceding discussion it is apparent that the extent of permissible chorus effect is intimately related to, and limited by, the particular tone quality employed. In the past, this has imposed a fundamental limitation on the permissible extent of the chorus effect.

According to the principles of our invention, this interrelationship and consequent musical limitation is completely removed by separately generating the fundamental and the harmonic overtones, which make up the various musical tone qualities, in the form of individual groups of sinusoidal harmonic generators with each group having closely related frequencies but whose percentages of pitch deviation are appropriate to their particular average frequency, and which percentages vary in a substantial manner over the audio frequency range under consideration.

For example, the chorus generators supplying the fundamental of a string tone may have a relatively large percentage of frequency deviation, the second harmonic generators a smaller percentage deviation, the third and fourth harmonic generators a still smaller percentage deviation, etc. Thus, by the utilization of the principles of this invention, we are able to achieve a truly theoretical maximum chorus effect for all tone qualities. This follows by simply considering that each of the harmonics taken separately is sinusoidal in character, and thus each group of harmonic generators has percentage deviations conforming to the pure sinusoidal tone curve in Fig. 1. As pointed out heretofore, this curve for sinusoidal tones produces the theoretically greatest permissible chorus effect. Thus each of the partials of the harmonically synthesized chorus string tone, as generated by the apparatus of our invention, has approximately the same pitch deviation as is permissible with the sinusoidal tone. The resulting string tone is far more pleasing, by virtue of its extensive chorus effects, than a similar string tone in which the percentage of pitch deviation is relatively constant for the fundamental and harmonics alike. The latter, of course, is the case in which several complex wave generators sound simultaneously, as for instance several "celeste" organ pipes.

The chorus effects of the usual complex musical tones, as synthesized by the apparatus of our invention, become unbelievably rich and full taking on a lovely liquid quality never before heard in all music. All traces of imperfections in

tuning as formerly perceived in the higher harmonic frequencies vanish, and in their place is substituted a pleasing chorus of undulations in the lower order harmonics. Heretofore, this latter effect has been impossible to achieve without objectionably upsetting the pitch deviation of the higher order harmonic chorus frequencies. This is because the percentage pitch deviation was inherently the same for the fundamental as well as its harmonics. The curves of Figs. 5 and 6 are based upon a chorus generating system having two generators for each pitch of the musical scale. When more than two generators are provided for each note, somewhat greater pitch differences between the generators of the extreme pitches is permissible, apparently because a greater portion of the energy will necessarily be at or near the nominal pitch.

The instrument of our invention preferably takes the form of an electrical organ similar to that disclosed in the patents to L. Hammond Nos. 1,956,350 and 2,159,505. In the latter patent there is shown a set of solo generators and a set of chorus generators for the electrical synthesis of various musical tone qualities. In the instrument disclosed in said patent the chorus generators provide fundamental and harmonic tones differing from the corresponding solo generators by a constant percentage in the order of .4%.

The instrument of our invention may be constructed in the manner disclosed in the aforesaid Patent 2,159,505 except for the fact that each of the tone wheel shafts will carry two pairs of chorus tone wheels. The switching mechanism and other general features of construction of the chorus generator and associated parts may be of the construction shown in said patent.

A representative portion of a chorus generator embodying the principles of the invention is shown in Figs. 1 and 2 as comprising frame plates 20 and 21 to which separator sheets 22 are secured. The separator sheets 22 form shielding compartments 24 in each of which are located two pairs of chorus generator tone wheels 26. These tone wheels 26, as shown in Fig. 2, are secured to hubs 28 which are non-rotatably secured to a shaft 30 mounted for rotation in suitable composition bearings 32 secured in the sheets 22. A gear 34 is mounted for rotation on the shaft 30 between the two hubs 28. A pair of springs 36, 37 are wound about the hubs 28 respectively and are precompressed so as to press against the opposite sides of the gear 34. These springs thus serve as a frictional and resilient driving connection between the gear 34 and its shaft 30.

As shown in Fig. 1, the driven gears 34 mesh with drive pinions 38 nonrotatably secured to an articulated main shaft 40. The shaft 40 is driven through a resilient driving connection 42 from a motor drive shaft 44 which may constitute the armature shaft of a synchronous or constant speed motor.

Permanent magnet rods 50 are adjustably secured in bushings 52 secured to the plate 21, and their inner ends, which are generally wedge-shaped, are held in position closely adjacent the peripheries of the tone or phonic wheels 26. Each of the permanent magnets 50 has a pickup coil 54 mounted thereon adjacent its wedge-shaped end.

In Fig. 3 there is illustrated a representative portion of the schematic wiring diagram of a complete organ, there being disclosed six solo generator tone wheels 56, 57, 58, 59, 60 and 61,

for generating frequencies corresponding to the fundamental, second, third, fifth, sixth and eighth harmonic partials respectively of a particular tone, for example, the tone having a pitch C2. Each of these solo generators includes a pickup magnet 50 and coil 54. The coils 54 are connected in series with condensers C62 and the primary winding of a transformer T63, to form a filter circuit having a resonant frequency corresponding to that of the generator. The secondary winding of each of the transformers T63 has a plurality of non-robbing or decoupling resistors R64 connected thereto.

In Fig. 3 there is also illustrated a plurality of pairs of chorus generator tone wheels 66, 67, 68 and 69. The pickup coils 54 of these pairs of chorus generator tone wheels are adapted to be connected in parallel with the pickup coils 54 associated with the solo generators 58 to 61 respectively upon closure of switches 72 which are preferably gang switches operable by means of a single manual control. A suitable gang switch of this type is shown in the aforesaid patent to Hammond No. 2,159,505.

A playing key C2, through an insulating actuator 74, is adapted to close a plurality of key switches 76. Each of the switches 76 comprises a flexible arm 78 connected to one of the resistors R64. The other contacts of the switches 76 consist of bus bars 80 which serve as collectors for the sub-octave, sub-fifth, fundamental, second, third, fourth, sixth, and eighth harmonic frequencies respectively. For illustrative purposes the bus bars 80 are shown as connected to bus bars 82 with which switch arms 84 are adapted to make contact upon depression of a preset key 86. The bus bars 82 are selectively connected to terminals 88 which are connected to suitably spaced taps on the primary winding 90 of a transformer T92. The secondary winding 94 of this transformer is coupled to output control circuits 96 and the latter are coupled to an amplifier 98 through output control devices 100. The amplifier energizes a speaker 102. The constructional details of the apparatus and circuits may be similar to those of the organ more fully described in the aforesaid Patents Nos. 1,956,350 and 2,159,505.

It will be clear that whenever the chorus effect is desired, the switches 72 are closed, thereby connecting each of the chorus tone wheel pickups in parallel with the solo tone wheel pickups. Thus closure of one of the key-operated switches 76 will cause transmission to the output of the organ of tone signals including not only the frequency of the solo generator which is that of the nominal pitch of the note, but also two additional frequencies generated by the chorus generators associated with the selected solo generator.

Referring to the chart of Figs. 4, 4a and 4b, it will be observed that it constitutes a tabulation of the various properties of the chorus generators.

Column I sets forth the musical designation of the note while column II represents the number of the solo generator (commencing with the note C as note No. 1), while column III indicates the number of teeth in the chorus generator driving gears or pinions 38. Column IV similarly indicates the number of teeth in the driven gears 34 associated with the different chorus generators.

Column V shows the number of high points on the phonic wheels 26. It will be understood that the peripheries of these tone wheels are

scalloped so as to generate substantially sine waves as they rotate past the pickup magnets. It will be noted that the first six pairs of chorus generator phonic wheels each comprises phonic wheels having 31 and 32 high points, whereas in the second group of six pairs of phonic wheels, each pair comprises a wheel having 44 high points and a wheel having 45 high points. In a similar manner, each series of six successive pairs of chorus tone wheel generators are similar. Because of this arrangement a substantial economy in the manufacture of the tone wheels is effected, since it is necessary to have only 16 different shapes of phonic wheels for producing the 96 different frequencies required in the chorus generator. It will also be noted that this selection of constants also permits the duplication of driving and driven gears to a very substantial extent.

Column VI shows the actual frequencies which are generated by the chorus generators, while column VII shows the frequencies generated by the solo phonic wheels associated with the chorus generators.

Column VIII sets forth the differences between the frequencies generated by the solo generators and those generated by their associated chorus generators. Column IX shows the ratio between the differences between the frequencies of column VIII and column VI, as a percentage of the frequency of the solo generator.

Column X shows the sum of the deviations of the chorus generators from the frequencies of the solo generators as a percentage of the solo generator frequencies.

From the frequency differences set forth in column VIII, it will be clear that such deviation is generally in the order of 10 C. P. S. From column X it will be apparent that there is a substantial tapering of the deviation of the chorus generator frequencies from the frequencies of their corresponding solo generators, this percentage deviation varying from a maximum of 3.178% to a minimum of .563%, the greater deviation i. e. in the order of more than 3% is utilized in the lower frequency spectrum, while the lesser frequency deviation is in the higher pitch range in which it has been found to be musically undesirable to have a wide frequency deviation.

By reference to the chart Figs. 4, 4a and 4b it will be clearly apparent that the deviations in frequency generated by the chorus generators conform generally to the pure sinusoidal tone curve of Fig. 5. The degree of correspondence is illustrated in Fig. 6 wherein the dash line curve corresponds generally to the pure sinusoidal tone curve of Fig. 5 and the irregular curve shown in full lines corresponds to the extent of deviation of the chorus generator frequencies from the solo generator frequencies when the apparatus is constructed in accordance with the chart of Figs. 4, 4a and 4b. From Fig. 5 it will be clear that the frequencies generated by the chorus generators correspond generally with respect to their deviation from the solo generator frequency to the extent considered desirable by most musicians.

For some uses of the organ, for example, when used in churches, it is not desirable to utilize chorus generators having the maximum permissible deviation from the solo frequencies, and for such organs it is preferable that the chorus generators for the notes 44 to 67 deviate from their solo frequencies by a relatively constant percentage, in the order of .4%, making a total

chorus frequency range of .8% of the solo frequency. The frequency deviation of the chorus generators of such organs might follow the dot dash curve shown in Fig. 6 for the notes 44 to 67, but would preferably follow the full line curve for chorus generators above the note 67. An organ constructed in this manner would constitute somewhat of a compromise between the instrument disclosed in said prior Patent 2,159,505 and an organ incorporating in full the features of the present invention. Such compromise is desirable in organs used for ecclesiastical music because of the traditional preference for the simpler tone qualities in music of this character.

The chart, Fig. 7, sets forth the modified chorus generator details for the notes 44 to 67, it being understood that the chorus generators for the notes 68 to 91 would be constructed in the manner indicated in the tabulation of Figs. 4a and 4b. From Fig. 7 it will be noted that the total percentage range of deviation of the frequencies of the chorus generators, as compared with the solo generator frequency, is in the order of .8% (column IX, Fig. 7), while the differences in the frequencies of the two chorus generators of a pair is in the order of 1.575% (column X, Fig. 7).

It will be understood that for entertainment uses, the chorus effect is preferably used to its full extent, whereas for church use the full chorus effect in the lower pitches is generally considered undesirable because the tones are too lively and unusual for liturgical and similar purposes. Likewise, for use in the home, some musicians may prefer not to have the full range chorus effect extend to the lower notes, but instead, may prefer to have a relatively narrow chorus range for the notes G₃ to F₅.

Referring to Figs. 4, 4a and 4b, it will be noted that the chorus generators are divided into groups of semi-octave range by double horizontal lines. It will further be noted that the numbers of teeth in the driving and driven gears for the first semi-octave correspond respectively to those of the second semi-octave (columns III and IV). By reference to column V (Fig. 4), it will be noted that the numbers of high points on the phonic wheels for the second semi-octave group differ from those in the first semi-octave group by a factor closely approximating the square root of 2, i. e. 1.414.

In a similar manner the third and fourth semi-octave groups, the fifth and sixth semi-octave groups, and the seventh and eighth semi-octave groups respectively utilize driving and driven gears having the same numbers of teeth. The numbers of the high points on the phonic wheels for each of these semi-octave groups differ from the numbers of high points on the phonic wheels for the next adjacent semi-octave group by a factor closely approximating the square root of 2. Because of this relationship it is possible to mount two pairs of phonic wheels on each driven shaft and to reduce by one-half the number of driving and driven gears required for the rotation of the chorus generators. It also makes it possible to use pairs of phonic wheels with the same numbers of high points for the chorus generators of each semi-octave group. The manufacture of the chorus generator apparatus is thus greatly simplified.

From the foregoing it will be clear that we have devised a chorus generating apparatus capable of producing musical chorus effects inherently unobtainable by any prior musical instrument in

that the degree of chorus effect varies throughout the musical scale in a general accordance with the response characteristics of the human ear. Thus each partial of each musical tone produced will have the most desirable degree of chorus frequencies added thereto. The overall effect of music produced by the instrument is thus of a vitally different character and a substantial improvement as compared with the music which may be produced by any other instrument.

While we have shown and described particular embodiments of our invention, it will be clear to those skilled in the art that quite a number of additional variations and modifications of the invention may be made without departing from the underlying principles thereof. We therefore desire, by the following claims, to include within the scope of our invention all such modifications and variations by which substantially the results of the invention may be obtained by the use of substantially the same or equivalent means.

We claim:

1. In an electrical musical instrument having electrical sine wave solo generators respectively generating frequencies of the notes of the tempered musical scale extending at least from the frequency 392 to 5924.57 cycles per second, and a plurality of electrical chorus generators, and means to cause said generators to generate frequencies respectively differing from those of the solo generators by different percentages, those in the lowest frequency range differing by a percentage in the order of 1.6, those in the higher frequency range differing by a percentage in the order of .28 and those in the ranges intermediate these extreme frequencies differing by percentages between 1.6 and .28.

2. In an electrical musical instrument having a set of solo generators generating sine waves of substantially the frequencies of the tempered musical scale, a plurality of chorus generators, and means to cause said generators to generate frequencies differing respectively from the frequencies generated by said solo generators, the frequency differences between the chorus generators and their respective solo generators being relatively small for the higher pitch notes and increasing progressively in descending the musical scale.

3. An electrical musical instrument having a plurality of electrical generators, there being a set of generators for each note of the musical scale within a predetermined gamut and means to operate, the generators of each set to cause them to generate frequencies differing from one another but having an average frequency substantially that of a note of the tempered musical scale, the maximum percentage deviation from the average of the frequencies generated by the generators of each set differing throughout the musical scale, there being a greater deviation at the lower end of the scale and a lesser deviation at the upper end of the scale.

4. In a chorus generator, the combination of a plurality of tone wheel shafts, two pairs of generator tone wheels mounted in spaced relation on each of said shafts, means for driving said shafts at constant speeds, the average number of high points on one pair of tone wheels on each shaft differing from the average number of high points on the other pair of tone wheels on such shaft by a factor in the order of the square root of 2.

5. In an electrical musical instrument, apparatus for producing a chorus effect comprising, a plurality of constant frequency solo generators

of relatively fixed pitch whose frequencies are those of the equal tempered scale, a plurality of chorus generators respectively associated with said solo generators, and means to cause the pitches of the chorus generators to be maintained accurately relative to the solo generators at such pitches that the chorus generators at the high frequency end of the scale generate frequencies which differ percentagewise from their respectively associated solo generators by a smaller factor than do the chorus generators at the lower frequency end of the scale.

6. In an electrical musical instrument, having a series of solo generators of electrical impulses at the frequencies of the notes of the tempered musical scale, a plurality of pairs of electrical chorus generators respectively connectable in parallel with said solo generators, means to cause said chorus generators to produce electrical impulses of frequencies differing from the frequencies of the solo generators by factors in the order of .0055 in the range about 1760 cycles per second, .0042 in the 2400 cycles per second range, .0040 in the 3500 cycles per second range, and .0028 in the 5000 cycles per second range, and means operable at will for electrically connecting said pairs of chorus generators respectively in parallel with said solo generators.

7. In an electrical musical instrument, having a series of solo generators of substantially sine wave electrical impulses at the frequencies of the notes of the tempered musical scale from approximately 392 cycles per second to approximately 5925 cycles per second, a plurality of pairs of chorus generators respectively connectable in parallel with said solo generators, means to cause said chorus generators to produce substantially sine wave electrical impulses of frequencies differing from the frequencies of the solo generators by about 6 to 8 cycles per second in lowest octave of the chorus generator gamut, by about 8 to 11 cycles per second in the next to the lowest octave, by about 9 to 13 cycles per second in the third lowest octave, and by about 11 to 24 cycles per second in the highest octave, and means for selectively connecting the outputs of said pairs of chorus generators respectively in parallel with the outputs of said solo generators.

8. An electrical musical instrument in which complex musical tones are produced by combining a plurality of harmonically related substantially pure sine waves, comprising, a plurality of solo electrical generators of substantially pure sine waves of the frequencies of the notes of the musical scale, a plurality of chorus electrical generators of substantially pure sine waves of frequencies differing from those generated by the solo generators by small percentages which decrease with increases in the frequencies generated, and selectively operable switch means for combining the electrical output of each chorus generator with the electrical output of the solo generator of the nearest frequency.
